UNITED STATES PATENT OFFICE.

BERNARR MACFADDEN, OF NEW YORK, N. Y.

HEATING AND HUMIDIFYING SYSTEM.

1,291,579.

Specification of Letters Patent. Patented Jan. 14, 1919.

Application filed April 19, 1917. Serial No. 163,307.

To all whom it may concern:

Be it known that I, BERNARR MACFADDEN, a citizen of the United States, residing in New York, in the county of New York and State of New York, have invented certain new and useful Improvements in Heating and Humidifying Systems, of which the following is a specification.

This invention relates to systems for humidifying and heating the air of rooms, buildings and the like.

One object of the invention is to provide a combined heating plant adapted to heat by radiation from either the smoke flues of the furnace or hot water radiators or both.

Another object is to provide means whereby heat may be extracted from the products of combustion in the chimney either by contact of said products with water pipes, or also directly with the water to be heated, whereby the products of combustion are washed and freed from solid matter.

Another object is to provide a system and radiators whereby the air is humidified and heated by direct contact with water exposed in open troughs or fountain jets of the radiator.

Another object is to provide a convenient, efficient and economical construction for such a radiator.

Another object is to provide a system adaptable to either the open trough radiator or the ordinary closed radiators.

A further object is to provide a conveniently constructed economical and efficient system accomplishing the above objects.

These and other objects will appear as the description proceeds, and it is particularly noted that various changes may be made in the construction and details thereof without departing from the scope of the invention as claimed.

In the accompanying drawing, showing by way of example, one of many possible embodiments of the invention,

Figure 1 is a diagrammatic view showing a vertical section of a building and the humidifying and heating system partly in elevation and partly in section.

Fig. 2 is a central vertical sectional view showing the open trough radiator.

The new system is shown applied to a building having floors 5, 6, 7, and a roof 8.

A hot water heater 9 is provided in the basement of the building, and discharges

its products of combustion into the chimney 10.

If the slide dampers 11 and 12 are open, as shown by the dotted lines, the combustion products pass directly out of the chimney. If, however, the slide damper 11 is closed, and the dampers 14 of the flue pipe 15 are open the hot products of combustion pass through the flue pipe 15 and give out to the rooms considerable heat that would, in ordinary systems, be otherwise wasted.

Water may be introduced into the system from the city mains through the pipe 16 and valve 18.

When the heat is to be extracted from the products of combustion by direct contact with the water, the water passes through the pipe 19, the motor driven pump 20 and the pipe 21 to the spray nozzles 22 and 24 in the box-like spray-flue 25, communicating with the upper part of the chimney and having an outlet flue controlled by the damper 26.

When the damper 26 is open and the damper 12 closed, the products of combustion pass through the spray flue and are washed and cooled by the sprays from the nozzles 22 and 24, a large per cent. of the heat being carried off in the drip water.

The bottom of the spray flue is adapted to hold the drip water from the sprays and the overflow through the pipe 28 to the filter 29 where carbon particles and the like are removed from the water.

From the filter the water passes through the pipes 30 and 31 (the valve 32 being closed and the valve 33 open) to the heat-exchanging coil 34 where the water is further heated by the hot gases of the chimney.

From the coil 34 the water passes through the pipe 35 to the heater 9, the valve 36 being open and the valve 37 closed. The water is additionally heated in the heater 9 and, the valve 41 being open and the valve 42 being closed, the water passes through the pipe 38 to the radiators 39 and 40, the latter to be described more in detail hereafter. From the radiators the water passes through the pipes 43, and 44 to the pipe 19 and thence to the pump 20 thus completing the circuit.

Both sets of nozzles 22 and 24 are directed to throw water onto the felts 45 stretched on horizontal bars 46 extending across the spray flue 25, whereby a sinuous path is provided in which the products of combustion are brought into intimate con-

tact with the water sprayed onto the felts, thus increasing the heat exchanging capacity of the apparatus.

By means of the valves 48 and 49 any of 5 the radiators 39 or 40 may be cut out of operation.

The radiators 40 have as their principal feature the exchange of heat from the water by direct contact of the water with the air 10 of the room to be heated. These radiators may be constructed in a variety of ways, for instance, as shown in Fig. 2 of the drawing, where the radiator comprises a plurality of 15 annular troughs 50, 51, and 52, each provided with an upwardly extending flange 54, on which rests the trough next above, except in the case of the top trough 52 which supports thereon the bowl 55.

The lowermost trough 50 is provided with 20 supporting legs 56 and an outlet pipe 58 leading to the pipe 44.

Extending across the opening formed by the bottom annular trough 50 is a disk-like web 59 provided with a central perforation 25 through which passes the inlet pipe 60, in turn passing through the bottom of the bowl 55 and terminating with a small orifice for furnishing a spray 61. The pipe 60 also 30 serves for holding together the various sections of the radiator by means of the collar 62 and the nuts 64.

The bowl 55 and the troughs 51 and 52 are provided with lips 65 whereby the water may drip to each trough below, the troughs 35 gradually increasing in diameter downwardly for this purpose.

The bowl and the troughs 51 and 52 are provided with small bleed holes 66. For the trough 50, the bleed hole 67 is in the outlet 40 pipe 58. By these bleed holes the water is entirely drained out of the trough when the troughs are to be put out of use, but they are not large enough to interfere with the normal operation of the radiator.

45 It will be noted that the inlet of the pipe 28 is well above the spray 61 so that there is always sufficient pressure for feeding this spray.

The valve 18 may be left very slightly 50 open to make up for the losses of evaporation. If an excess of water passes into the spray flue, it may overflow through the overflow pipe 68.

If it be deemed desirable to use the system 55 without heating by direct air and water contact, the damper 12 is opened and the damper 26, the filter valve 69, the pump valve 70 and the valves 36, 41 and 49 are closed. In this case the water passes into the heater 60 through the pipe 19 and out through the pipe 71, thence through the coil 34, pipe 72, pipe 38, radiators 39, pipe 43, and pipe 19 to the heater, thus completing the circuit, the pipe 38 being extended to the expansion 65 tank 74.

It is understood that while only a few radiators and heating flues are shown, that the number that may be used is not limited. Where very many heating flues are used, means such as the centrifugal fan 75 may be 70 used for forcing the draft of the heater. This fan receives air from the outside of the building and forces it into the ash pit of the heater.

I claim:

1. In a system of the character described, the combination of a heater furnace; a flue receiving products of combustion from the heater furnace; means for ejecting sprays of water into the flue whereby the water 80 is heated; means for collecting said heated water; a heat exchanging coil in said flue receiving said heated water; and radiators receiving the water from said coil.

2. In a system of the character described, 85 the combination of a heater furnace; a flue receiving products of combustion from the heater furnace; means for ejecting sprays of water into the flue whereby the water is heated; means for collecting said heated 90 water; a heat exchanging coil in said flue receiving said heated water; radiators receiving the water from said coil; and means for conducting the water from said radiators to the spraying means.

95 3. In a system of the character described, the combination of a hot water heater having a heating furnace; a flue receiving the products of combustion from said furnace; nozzles for spraying water into said flue; a means for collecting the sprayed water; a coil in said flue receiving the water from the collecting means and conducting it into said heater; and radiators receiving the water from the heater.

105 4. In a system of the character described, the combination of a hot water heater having a heating furnace; a flue receiving the products of combustion from said furnace; nozzles for spraying water into said flue; means for collecting the sprayed water; a coil in said flue receiving the water from the collecting means and conducting it into said heater; radiators receiving the water from the heater; and means for conducting the 110 water from the radiators to said nozzles.

115 5. In a system of the character described, the combination of a hot water heater having a heating furnace; a flue receiving the products of combustion from said furnace; nozzles for spraying water into said flue; means for collecting the sprayed water; a coil in said flue receiving the water from the collecting means and conducting it into 120 said heater; radiators receiving the water from the heater; a pump; pipes conducting the water from the radiators to the pump; and a pipe for conducting the water from the pump to the nozzles.

125 6. In a system of the character described, 130

the combination of a hot water heater; a chimney flue receiving the products of combustion from the heater; a spray flue leading off from the upper part of the chimney flue; nozzles in the spray flue; a heat exchanging coil in the lower part of the chimney flue and fed from said spray flue; radiators fed from said coil; and means for pumping water from said radiators to the spray nozzles.

7. In a system of the character described, the combination of a hot water heater; a chimney flue receiving the products of combustion from the heater; a spray flue leading off from the upper part of the chimney flue; nozzles in the spray flue; a heat exchanging coil in the lower part of the chimney flue and fed from said spray flue; a pipe connecting the lower part of said coil with the hot water heater; a radiator connected to the hot water heater; and means for pumping water from the radiator to the nozzles.

8. In a system of the character described, the combination of a hot water heater; a heat exchanging coil communicating with the heater; feeding means for feeding water to said coil; a radiator comprising an open trough receiving water from said heater; and means for circulating water from said radiator to said feeding means.

9. In a system of the character described, the combination of a hot water heater; a heat exchanging coil communicating with the heater; circulating means for feeding water to said coil; a radiator comprising an open trough receiving water from said heater; and means for conducting water from said radiator to said circulating means, said radiator being below the level of the inlet end of said coil.

10. In a system of the character described, the combination of a hot water heater; a chimney flue receiving products of combustion from the hot water heater; a heat exchanging coil in said flue communicating with the heater; means for feeding water to the upper end of said coil; and a radiator comprising means for holding water open to the atmosphere and communicating with said heater.

11. In a system of the character described, the combination of a hot water heater; a chimney flue receiving products of combustion from the hot water heater; a heat exchanging coil in said flue communicating with the heater; means for feeding water to the upper end of said coil; and a radiator comprising means for holding water open to the atmosphere and communicating with said heater, said radiator being below the level of the upper end of said coil.

12. In a system of the character described, the combination of a main pipe; a closed radiator connected to said main pipe; an

open radiator connected to said main pipe; a water heating means adapted to supply hot water to said main pipe; a pipe connecting said heating means to said closed radiator whereby a water circuit is formed in said main pipe, said closed radiator, said connecting pipe and said heating means; circulating means for introducing water into the heating means above the level of the open radiator; and means for conducting water from the open radiator to the circulating means.

13. In a system of the character described, the combination of a main pipe; a closed radiator connected to said main pipe; an open radiator connected to said main pipe; a water heating means adapted to supply hot water to said main pipe; a pipe connecting said heating means to said closed radiator whereby a water circuit is formed in said main pipe, said closed radiator, said connecting pipe and said heating means; circulating means for introducing water into the heating means above the level of the open radiator; means for conducting water from the open radiator to the circulating means; and valves whereby said closed radiator and said connecting pipe or said open radiator may be cut off from said main pipe.

14. In a system of the character described, the combination of a hot water heater; a chimney flue receiving the products of combustion from the heater; a heat exchanging coil in the lower part of the chimney flue; a feeding means for feeding water to the upper part of said coil; a connecting pipe establishing communication between the lower part of the heater and said feeding means; a pipe connecting the lower part of the coil with the lower part of the hot water heater; a main pipe extending upwardly from the upper part of the heater; open trough radiators and closed radiators laterally connected to said main pipe; drain pipes connecting the outlet of the radiators with said connecting pipe; and a valve for closing said connecting pipe from communication with the lower part of the heater.

15. In a system of the character described, the combination of a hot water heater; a chimney flue receiving the products of combustion from the heater; a heat exchanging coil in the lower part of the chimney flue; a feeding means for feeding water to the upper part of said coil; a connecting pipe establishing communication between the lower part of the heater and said feeding means; a pipe connecting the lower part of the coil with the lower part of the hot water heater; a main pipe extending upwardly from the upper part of the heater; open trough radiators laterally connected to said main pipe; drain pipes connecting the outlet of the radiators with said connecting pipe; a valve for closing said connecting pipe

from communication with the lower part of the heater; valves in said connecting pipe and between the feeding means and said coil; a valved pipe connecting the upper part of the heat exchanging coil with the main pipe; a valved pipe connecting the lower part of said coil with the upper part

of the heater; and an expansion tank connected to said main pipe.
